UNITED STATES PATENT OFFICE.

GROVER G. TUTTLE, OF PHILLIPSBURG, NEW JERSEY, ASSIGNOR TO INGERSOLL-RAND COMPANY, OF JERSEY CITY, NEW JERSEY, A CORPORATION OF NEW JERSEY.

HANDLE FOR ROCK DRILLS.

Original application filed March 5, 1923, Serial No. 622,748. Divided and this application filed October 18, 1924. Serial No. 744,462.

This invention relates to fluid pressure operated rock drills of the hammer type, but more particularly to air feed control for the feeding element of a stope drill.

5 This application is a division of applicant's copending application, Serial No. 622,748, filed March 5, 1923.

Stope drills are usually provided with a laterally extending handle which the 10 operator turns to provide rotation for the steel. In the case of self rotating tools, this handle is used for the purpose of holding the drill from rotating while the steel is turned in the rock. For maintaining the 15 steel against the work, there is ordinarily provided an air feed supplied with motive fluid from the main source for the throttle or other controlling valve for the drill so that when the piston of the drill is operating, 20 air is simultaneously being fed to the air feed cylinder. It is a common occurrence for the drill steel to stick in the hole while drilling and the most convenient way of loosening the steel is to continue operation 25 of the hammer piston in the drill cylinder, and at the same time to release the pressure in the air feed cylinder allowing the steel to be withdrawn somewhat. Almost unwillingly, the operator pulls down on the 30 rotation handle when the drill sticks sensing that the steel must be withdrawn from the hole in order to continue drilling. Under these conditions, it is very inconvenient for the operator to operate the throttle valve because it is the usual practice to arrange the 35 throttle valve so that the drill stops hammering before the air feed is relieved.

It is an object of this invention to provide an air feed release which is controlled by 40 the unconscious action of the operator in pulling down on the rotation handle when the sticking occurs.

Further objects of the invention will appear from the following description taken 45 in conjunction with the accompanying drawings, in which—

Figure 1 is a side elevation partly in vertical section of a stope drill embodying the 50 invention,

Figure 2 is an enlarged detailed view in longitudinal section of a portion of the rotation handle shown in Figure 1 wherein the grip supported by the handle extends downwardly, and

55 Figure 3 is a detailed view in longitudinal

section of a rotation handle reversed so that the grip extends upwardly but still operates to release the air feed when the grip is pulled downwardly.

Referring to the drawing, a stope drill is 60 illustrated in Figure 1 having the usual cylinder A and front head B carrying the drill steel C. The front head B is attached to the cylinder A by the usual side bolts D and the cushion springs E. The cylinder 65 A and its operative parts comprise the percussive element (not shown) of the tool for imparting the impact blows of the piston to the drill steel C. The drill steel may be rotated in any suitable manner, but in this instance is adapted to be rotated by a gear motor (not shown) enclosed by the gear casing F.

The feeding element comprises the usual 70 feed cylinder G in which the piston H is adapted to slide. The piston rod J, which carries the rock engaging pointer K, is secured to the piston H. Between the gear casing F and the feed cylinder G is located the head block L to which is secured a 75 laterally extending rotation handle O whereby the operator may hold the machine against rotation with the drill steel C. In this instance, the handle O is provided with a portion O' extending at right angles either 80 up or down as shown in Figure 1. Motive fluid for operating the tool is supplied through the inlet L' and simultaneous admission of motive fluid to the cylinders G and A is controlled by a suitable throttle 85 valve (not shown) having a valve handle P.

The portion O' of the rotation handle O is provided with a sleeve or grip Q which is rotatable for the convenience of the operator and is adapted to slide vertically on the 90 portion O' being held against removal by the cap R. The grip Q is preferably provided with end flanges Q' to prevent slipping of the operator's hand from the grip. In sliding up and down, the grip Q is adapted 100 to open or close as the case may be, the valve S reciprocable transversely through the portion O' for controlling a passage way T leading from the air feed cylinder G to atmosphere, preferably through a bore U in the 105 cap R. To this end the portion O' of the rotation handle is provided with a transverse bore V and a counter bore W. The valve S is adapted to seat at the junction of the bore V and the counter bore W and is 110

provided with a head X adapted to be pushed inwardly by the cam like action of a spherical groove Y on the inside of the grip Q. Normally, the valve S is held closed by means of a suitable spring S' pressing between the body Z of the valve S and a hollow screw b threaded in the counter bore W. The grip Q is normally held up by a coil spring c. The coil spring c encircles the free end of the portion Q' and in this instance bears with one end against the grip Q and at its other end is seated on the cap R, so that in order to open the valve S the grip Q must be pulled downwardly. Rotation of the grip Q does not affect the valve S since the groove Y is of an annular form.

When the grip Q is pulled down, the groove Y pushing against the head X of the valve S, the air from the cylinder G is then permitted to leak out through the passage T past the valve S into the bore V and thence through a passage d to atmosphere. The passage T is preferably of larger cross sectional area than the port in the throttle valve which admits air to the feed cylinder g. Thus, since the air is permitted to leak out of the cylinder G as fast as it is fed, the drill drops somewhat as long as the operator keeps the grip Q pressed down against the force of the spring c. There is no danger of the tool dropping too far because the operator naturally pulls up on the grip Q when he desires the air feed to operate again.

The grip Q may extend either downwardly from the rotation handle O as shown in Figure 2 or upwardly as shown in Figure 3. The operation of the handle will be the same, it being merely necessary if this change is desired to remove the cap R and reverse the grip Q with the spring c on the angularly extending portion O'.

I claim:—

1. A rock drill comprising a pressure fluid feeding element, a hollow laterally extending rotation handle in communication with the feeding element and having a vertically extending portion, a longitudinally slid able grip having end flanges and adapted to rotate on said portion, an internal spherical groove in said grip, a spring encircling the free end of said portion normally holding said grip upwardly, and a valve in said portion contacting with the spherical groove and operable by the downward motion of said grip with respect to said portion to control the pressure fluid in said feeding element through said hollow handle and through the portion to the atmosphere.

2. A rock drill comprising a pressure fluid feeding element, a hollow laterally extending rotation handle in communication with the feeding element and having a vertically extending portion, a longitudinally slid able grip having end flanges and adapted to rotate on said portion, an internal spherical groove in said grip, a spring encircling the free end of said portion normally holding said grip upwardly, a valve reciprocable transversely through the portion constantly contacting with the spherical groove and adapted to be opened by said groove upon downward movement of the grip on the portion for releasing pressure fluid from the feeding element through the hollow handle and the portion to the atmosphere, and a cap in the free end of the portion to form a seat for the spring and for preventing removal of the grip from the portion.

In testimony whereof I have signed this specification.

GROVER G. TUTTLE.
